UNITED STATES PATENT OFFICE.

FRANK J. SMITH, OF SAN FRANCISCO, CALIFORNIA.

CAN-ENDING MACHINE.

1,034,153.

Specification of Letters Patent. Patented July 30, 1912.

Application filed August 19, 1911. Serial No. 644,949.

To all whom it may concern:

Be it known that I, FRANK J. SMITH, a citizen of the United States, residing in the city and county of San Francisco and State 5 of California, have invented new and useful Improvements in Can-Ending Machines, of which the following is a specification.

My invention relates to the class of can ending machines especially intended for use 10 in can factories, where one end alone is applied, the other end of the can being left open for the application of its head in the cannery, after the cans are filled.

My invention concerns a machine of the 15 "double seaming" type, in which the flanges of the can body and end are bent and doubled upon themselves by the pressure of properly grooved rolls.

The object of my invention is to provide 20 a machine of this class in which the operation is a continuous one, effected during the continuous rotation of the machine, with no intervening periods of rest, whereby the capacity of the machine is greatly increased.

25 The invention consists of the parts and the construction and combination of parts as hereinafter more fully described and claimed, having reference to the accompanying drawings, in which—

30 Figure 1 is a plan view of my machine, the seaming-heads at the upper and lower positions of revolution being omitted. Fig. 2 is a side elevation, the seaming heads and the clamping jaws at the side positions of revolution being omitted. Fig. 3 is a vertical section, enlarged, on the line A—B, of Fig. 1, looking in the direction of the arrow. Fig. 4 is a section, enlarged, taken on the line C—D, of Fig. 2, 40 looking in the direction of the arrow. Fig. 5 is an elevation, enlarged, of the seaming-head from one side. Fig. 6 is a plan view of the same with the shifter head removed. Fig. 7 is an elevation of the same 45 at right angles to the elevation of Fig. 5. Fig. 8 is a top view of one of the clamping jaws. Fig. 9 is a section on the line E—F, of Fig. 2, looking in the direction of the arrow. Fig. 10 is a vertical sectional view 50 of the gearing for operating the main shaft and the seaming heads. Fig. 11 is a front elevation of the carrier 11.

The frame of the machine is composed of a stand 1, end plates 2 and a top bar 3, as 55 seen in Figs. 1, 2 and 3. Secured to one side of the top bar 3 are brackets 4 which carry

the angle irons 5 forming the vertically disposed can-body delivery chute 6. At one side of this chute, as shown in Figs. 1 and 2, is the vertically disposed can-head delivery chute 7. In Fig. 1, a can 8 and a can-end 9 are shown in their respective chutes. Mounted in the end plates 2 of the machine frame is the horizontally disposed main shaft 10. Upon this shaft is keyed the combined can-body and can-end carrier 11. As shown in Fig. 3, this carrier is a disk formed with a plurality (here shown as four) of equidistant semicircular notches or pockets 12 in its periphery, which said notches, as 70 shown clearly in Figs. 1, 2 and 11, are stepped or formed in three diameters; the smallest step or diameter 13 being adapted to receive the end of the can-body, the intermediate step 14 being adapted to receive the 75 flange of said can-body end, and the largest step 15 being adapted to receive the can-end.

The position of the carrier 11 with respect to the can-body and can-end chutes 6 and 7, as shown in Figs. 1, 2 and 3, is such 80 that the lowermost of the vertical columns of bodies and ends rest temporarily upon the periphery of the carrier, as seen in Fig. 3, and then, as the carrier revolves, they 85 will drop by gravity into the notch or pocket 12 which then comes into place, and will seat themselves in their respective steps, as above explained; in which position the head and body are in alinement and ready to be assembled. The carrier 11 thus supports 90 and guides one end of the can-body. The presser plate 77 at this time moves against the end while it is in this position, and holds the end in the semi-circular disk while the can-body is being pushed into the end, then 95 the presser plate travels back in line of the double seaming rolls at the same time the jaws bring the can-body up; all of this moving of the plate 77 being done by the cam 80. In order to support its other end, to 100 clamp it against rotation on its axis, and to force it into its end, the following constructions are employed: Secured upon the main shaft 10 and rotating therewith is a four-armed spider 16, each arm of which 105 at its extremity carries a bearing 17, in which is mounted and adapted to slide in a direction parallel with the main shaft 10, the stem 18 of the clamping jaws. Each clamping jaw is duplex; the parts being 110 complementary and semicircular, one, designated at 19, being a fixed member and the

other 20 a movable one. This jaw 20 may be mounted on a slide, in a parallel line with the axis of the can or at an angle thereto. In the present illustration this member is so mounted as to swing. The swinging member is the outer one and is hinged to the stem 18 by means of the pivot 21 in a projection 22 of said swinging member, as is most clearly seen in Figs. 1 and 8. Thus, 10 the jaws are adapted to open and close by the swinging of one member from, and to, the other. When a jaw is in the lowest position of the revolution of the spider 16, this swinging member 20 is swung back, as 15 seen in Figs. 2 and 4, and this open position of the jaw continues, as is shown in Fig. 4, until it has passed the point at which the bodies and ends are fed in, as may be seen by comparing Fig. 4 with Fig. 3. As a result of this, the can body will be received in 20 the semi-circle of the fixed member of the jaw; it being noted that the jaws of the spider 16 and the notches of the carrier 11 are in alinement in a direction parallel with 25 the axis of the can.

After the can-body has been received by the fixed member 19 of the jaw, the swinging member 20 begins to close in upon the can-body; and when it has reached the 30 upper point of revolution, said swinging jaw is fully closed, as seen in Figs. 2 and 4, and the can body is tightly clamped and continues thus, as seen in Fig. 4, until relieved near the bottom position of revolution by swinging open the member 20, whereupon the can with its assembled and seamed end falls out of the fixed member by gravity and is delivered to the discharge runway 23.

40 With this brief outline of the operation of the jaws, the mechanism for effecting such operation will be readily understood. On the back of the projection 22 of the swinging jaw-member 20 is a stud and roller 24. Referring now to Fig. 2, a standard 25 is secured to the frame stand 1 and to this standard is secured a grooved cam 26 which, as seen in Fig. 4, is concentric with the axis 45 of the spider 16 from the lowest portion of revolution up through an arc past the point of can entrance and nearly to the upper position of revolution; then the cam begins to twist, as shown in Figs. 1 and 4 at 27, until the top is reached, when it has made a quarter turn. The bottom end of said cam also has a quarter twist, but is broken away as 50 shown at Fig. 4, and will be explained later.

As the roller 24 on the projection 22 of the swinging jaw-member 20 moves along the 60 cam 26 near its lower end, as seen in Fig. 2, the twisted part being cut away, and as indicated in dotted lines in Fig. 4, travels upward in the concentric portion of the cam, causing the jaw-member 20 to remain open. After the can-body has been received

in the fixed jaw-member 19, the roller 24, reaching the twisted portion 27 of the cam 26 and traveling therein, causes the swinging jaw-member 20 to close upon the can, so that when the top is reached the can-body is 70 clamped between the two jaw-members. Now, in order to positively hold the swinging jaw-member 20 closed during the other half of the revolution, there is a roller 28 on the back of said jaw which, as seen in Fig. 75 4, enters behind and is held by a fixed guard rail 29 secured to the top bar 3 of the frame of the machine, which rail extends concentric with the axis of the spider 16 down to a point near the bottom, where at 30 it 80 terminates, as the roller 24 enters the twisted lower end of the cam 26, thereby swinging jaw 20 into an open position, as seen in Figs. 1, 2 and 4.

When the can-body has been clamped by 85 the jaws, it is pushed bodily in the line of its axis, so that, sliding in the notch 12 of the carrier, it enters the end 9, and both can-body and loosely fitted end, held firmly between the clamping jaws and the presser 90 plate, are pushed still farther until the end of the body and its end are free of the carrier and are in position to be acted upon by the seamer rolls. This pushing forward of the body and end is effected, by causing the 95 clamping jaws to slide forward. As has been previously stated, the stem 18 of the jaws is slidably mounted in a bearing 17 on the extremity of the arm of the spider 16.

To prevent any tendency to rotation, the 100 fixed jaw-member 19, as shown best in Fig. 8, is fitted with two side rods 31, extending parallel with the stem 18, and the other ends of said rods and said stem are united in a cross head 32. The bearing 17 is provided 105 with ears 33, through which the side rods 31 pass and in which they slide. The cross head 32 is fitted with a roller stud 34 which, as shown in Figs. 1 and 2, travels in a cam 35 secured to the end plate 2 of the machine 110 frame. This cam is fashioned to push forward and to retract the clamping jaws at proper times.

36 are the seaming heads. There are four of these, corresponding and in line with the 115 carrier notches 12 and the clamping jaws 19 and 20. Each head is provided with a pair of grooved seaming rolls 37 adapted to be thrown into action to press upon the flanges of the assembled end and can-body, 120 and double seam them in a manner now well known. These heads revolve as a series about the axis of the horizontal main shaft and with said shaft, and in unison with the carrier 11 and the series of clamping jaws. Each seaming head 36 is carried by a shaft 38, Figs. 5, 7 and 10, which shaft, as shown in Fig. 10, is carried by and is journaled in a bearing 39 in the extremities 125 of the arms of a spider 40 secured upon the 130

main shaft. Thus, the seaming heads are caused to revolve as a series, and each head may have rotation on its own axis, thereby accompanying the cans and while so doing revolving about them to effect the seaming.

Referring to Figs. 10 and 2, 41 is a power shaft, having a pulley 42 and a clutch 43. Upon the power shaft is a small gear 44 which meshes with a large gear 45 on the main shaft 10, whereby said shaft is driven at relatively low speed but with continuous motion. Upon the power shaft 41 is also mounted a large gear 46 which meshes with a small gear 47 on one end of a sleeve 48, which is loosely mounted upon the main shaft and is rotatable thereon. The other end of this sleeve 48 has a large gear 49 which meshes with a small gear 50 upon each of the shafts 38 of the seaming heads 36. Thus a relatively fast rotation is imparted to the seaming heads. In order to stiffen the support of the seaming-head shafts 38, there is another spider 51, which is loosely mounted upon the sleeve 48. In the arms of this spider the shafts 38 are also journaled, and said spider is connected with the main spider 40 by yokes 52.

In order to throw the seaming rolls 37 of the heads 36 into and out of action, the parts are constructed as follows: Referring to Figs. 5, 6 and 7, in the seamer head are two oppositely mounted rock shafts 53 passing through the head. The ends of these shafts which project from the face of the seamer head have cranks 54 in the ends of which seaming rolls 37 are mounted. The other ends of the rock shafts 53 have cranks 55. The seamer head has side brackets 56, in which are journaled rock pintles 57. On these rock pintles are secured cranks 58, the ends of which are forked over studs 59 projecting from lugs 60 of sleeves 60', which sleeves are mounted to slide in bearings 59' on the head 36. Passing through the sleeves 60' are rods 58', said rods being connected at one end to the cranks 55 of the rock shafts 53. The sleeves 60' slide upon these rods, and the ends of said sleeves are adapted to come in contact with nuts 57' adjustably fitted on the rods. Therefore, if the pintles 57 be rocked, the seaming rolls 37 will be thrown out to their work and again withdrawn therefrom, and the limits of their throw may be varied by adjusting the nuts 57' on the rods 58'. To rock the pintles 57 there is a shifter head 61 feathered upon the shaft 38 of the securing head, said shifter head having on opposite sides the ways 62. In these ways, as seen in Fig. 5, play rollers 63, secured to cranks 64 which are secured upon the pintles 57. When this shifter head is moved along the shaft 38, which carries it, it will rock the pintles 57.

To shift the head 61, the following connections are made: Referring to Figs. 2 and

9, 65 is a gear which is loosely mounted on the main shaft 10, and has connected with it a cam 66. Shifting levers 67 are pivoted at 68 to brackets 69 secured to the spider 40. These levers have forks 70 at one end, which engage an annular groove 71 of the shifter head 61. The other ends of the levers have roller studs 66' which play in the cam 66. If now the cam 66 be held against rotation, the shifting levers 67, revolving as they do, will be swung on their pivots 68, and will thereby move the shifter head 61 back and forth. To thus hold the cam 66 against rotation, by which is meant relative rotation, there is a shaft 72, which passes from one end of the machine through the spider 16, as seen in Fig. 4, and through a hole 11' in the carrier 11, and is mounted at its other end in a bearing 73 secured to the main shaft 10. This shaft 72 has at its outer end a gear 74 which meshes with a stationary gear 75 fixed upon the machine frame. At its other end the shaft 72 has a gear 76 which meshes with the gear 65 loosely mounted on the main shaft 10, and which has fixed to it the cam 66. It will now be seen that by properly proportioning the gears 65, 76, 74 and 75, the gear 75 being a stationary one, the effect will be to hold the loose gear 65 in a fixed relation to the gear 75, which relation is a relatively stationary one. Thus, the cam 66 is held fixed.

77 is the presser plate which moves up against the end and holds it firmly in the plate 11, while the can-body is being pushed into it. It is then timely moved back in unison with the clamping jaws until the can-body and end are in a position for the seaming operation. The plate 77 is carried by the stem 78 which is slidably mounted in the seamer head shaft 38 and projects from the outer end of said shaft. A stud and roller 79 are mounted on the projecting end of the stem and play in a cam 80 carried by the end plate 2 of the machine frame.

The machine operates as follows: The operation is a continuous one in contradistinction to an intermittent motion in which periods of rest are provided to allow time for certain functions to be performed. The clamping and the seaming devices accompany the cans and perform their functions while traveling. The can-bodies and the can-ends roll by gravity into successive notches 12 of the carrier 11, and are therein aligned. The presser plate 77 is moved up to the end holding it firmly in the notch. The can-bodies at their other ends drop into and rest upon the fixed clamping jaw members 19. Then the swinging jaw-members 20 come into action and the can-bodies are clamped. Then the clamping jaws are moved linearly and the can-body is forced into the end and both can-body and can-end are moved still further to a position for the

70

130

action of the seaming rolls 37; these are thrown into their work and the flanges are seamed. All this time the cans and all the operating parts are traveling, and near the completion of the cycle the cans are released and drop out by gravity. The presser plate 77 performs three functions: First, it forms a guide for one side of the end as it drops from the chute into the carrier notch 15. Second, after the end has dropped into the notch 15, the plate moves into the end, holding it in place until the can-body is assembled with the end. Third, it moves back with the end until the end and can-body are in line with the seaming rolls and holds the end firmly in place while it is being seamed onto the body.

Having thus described my invention, what I claim and desire to secure by Letters Patent is—

1. In a can ending machine, the combination of a carrier fashioned to receive and aline a can body and its head, means for assembling the body and head and a clamping jaw to hold them against rotation on their axes, a device rotatable about the assembled body and head for seaming their flanges, and means for imparting to said carrier, assembling and holding means, and seaming device, a continuous revolution in unison about a horizontal common axis.

2. In a can ending machine, the combination of a peripherally notched carrier adapted to receive and aline in its notch a can-body and its head, means for clamping said can-body and pushing it into its head, an opposing presser plate for holding the head in its notch while the can body is being pushed into it and holding in conjunction with the clamping means the assembled body and head against rotation on their axes, a device rotatable about the assembled body and head for seaming their flanges, and means for imparting to said carrier, clamping means, presser plate, and seaming device, a continuous revolution in unison about a common horizontal axis.

3. In a can ending machine, the combination of a peripherally notched carrier adapted to receive and aline in its notch a can-body and its head, said notch being of three steps, one for the can-body, one for its flange, and one for the head, means for assembling the body and head and holding them against rotation on their axes, a device rotatable about the assembled body and head for seaming their flanges, and means for imparting to said carrier, assembling and holding means, and seaming device, a continuous revolution in unison about a common axis.

4. In a can ending machine, the combination of a peripherally notched carrier adapted to receive and aline in its notch a can body and its head, said notch being of

three steps, one for the can body, one for its flange and one for the head, means for clamping said can-body and pushing it into its head, an opposing presser plate for forcing the head on the can-body and holding, in conjunction with the clamping means, the assembled head and body against rotation on their axes, a device rotatable about the assembled head and body for seaming their flanges, means for imparting to said carrier, clamping means, presser plate, and seaming device, a continuous revolution in unison about a common horizontal axis.

5. In a can ending machine, the combination of a peripherally notched carrier adapted to receive and aline in its notch a can-body and its head, a duplex clamping jaw alined with the notch of the carrier and movable in said line, said clamping jaw being composed of a fixed member adapted to receive the can-body as it enters the carrier, a swinging member adapted to close upon and to release said can-body, means for holding open the swinging member to permit the entrance of the can-body to the fixed member, means for closing said swinging member upon the can-body, means for sliding said clamping jaw lineally to push the can-body into its head, an opposing presser plate for preventing the head being moved out of the notch while assembling and, acting in conjunction with the clamping jaw, to hold the can and head against rotation on their axes, a device rotatable about the assembled body and head for seaming their flanges, and means for imparting to said carrier, clamping jaw, presser plate and seaming device a continuous revolution in unison about a common axis.

6. In a can ending machine, in combination with a carrier adapted to receive and aline a can body and its head, and means for effecting the seaming of their flanges when assembled, means for clamping the can-body and pushing it into its head preparatory to the operation of the flange seaming means, said means consisting of a duplex clamping jaw composed of a fixed member, and a swinging member, a stem on said fixed member and a bearing in which said stem is slidably mounted, a rotatable shaft upon which the carrier and the bearing for the clamping jaw stem are mounted, whereby they revolve in unison, means actuated by the revolution of the clamping jaw for closing and opening the swinging member of said jaw, and means also actuated by said revolution for lineally reciprocating the sliding stem of the clamping jaw.

7. In a can ending machine, in combination with a carrier adapted to receive and aline a can-body and its head, and

- means for effecting the seaming of their flanges when assembled, the means for clamping the can-body and pushing it into its head preparatory to the operation of the flange seaming means, consisting of a duplex clamping jaw composed of a fixed member, and a swinging member, a stem on said fixed member, and a bearing in which said stem is slidably mounted, a rotatable shaft upon which the carrier and the bearing for the clamping jaw stem are mounted whereby they revolve in unison, means actuated by the revolution of the clamping jaw for closing and opening the swinging member of said jaw, consisting of a fixed twisted cam and a roller stud on the swinging jaw-member engaging said cam, a fixed guard rail and a second stud on the swinging jaw-member engaging said rail, and means also actuated by said revolution for lineally reciprocating the sliding stem of the clamping jaw.
8. In a can ending machine, in combination with a carrier adapted to receive and aline a can body and its head, and means for effecting the seaming of their flanges when assembled, the means for clamping the can-body and pushing it into its head preparatory to the operation of the flange seaming means, said means consisting of a duplex clamping jaw composed of a fixed member, and a swinging member, a stem on said fixed member and a bearing in which said stem is slidably mounted, a rotatable shaft upon which the carrier and the bearing for the clamping jaw stem are mounted, whereby they revolve in unison, means actuated by the revolution of the clamping jaw for closing and opening the swinging member of said jaw, and means also called into action by said revolution for lineally reciprocating the sliding stem of the clamping jaw, consisting of a fixed cam, and a stud on the sliding stem engaging therewith.
9. In a can ending machine, in combination with a carrier adapted to receive and aline a can body and its head, and means for effecting the seaming of their flanges when assembled, the means for clamping the can-body and pushing it into its head preparatory to the operation of the flange seaming means, consisting of a duplex clamping jaw composed of a fixed member, and a swinging member, a stem on said fixed member, and a bearing in which said stem is slidably mounted, a rotatable shaft upon which the carrier and the bearing for the clamping jaw stem are mounted whereby they revolve in unison, means called into action by the revolution of the clamping jaw for closing and opening the swinging member of said jaw, said means consisting of a fixed twisted cam, a roller stud on the swinging jaw-member engaging said cam, a fixed guard rail and a second roller on the
- means also called into action by said revolution for lineally reciprocating the sliding stem of the clamping jaw, consisting of a fixed cam, and a stud on the sliding stem engaging therewith.
10. In a can ending machine, the combination of a carrier adapted to receive and aline a can-body and its head, means for clamping and pushing the can-body into its head, a rotatable shaft upon which the carrier and clamping means are mounted whereby they revolve in unison, a flange seaming device, also mounted upon said shaft and revolving in unison with the carrier and clamping means, said flange seaming device comprising a rotatable shaft, a head carried by the shaft, a rock shaft in the head, having a crank on each extremity, a grooved seaming roll carried by one of said cranks, a shifter head slideable on the shaft of the seaming head, power transmitting connections between said shifter head and the other crank of the rock shaft of the seaming head, adapted to rock said shaft to throw its seaming roll into and out of action, means for operating said shifter head, and means for rotating the shaft of the seaming head.
11. In a can ending machine, the combination of a carrier adapted to receive and aline a can-body and its head, means for clamping and pushing the can-body into its head, a rotatable shaft upon which the carrier and clamping means are mounted whereby they revolve in unison, a flange seaming device also mounted upon said shaft and revolving in unison with the carrier and clamping means, said flange seaming device comprising a rotatable shaft, a head carried by the shaft, a rock shaft in the head, having a crank on each extremity, a grooved seaming roll carried by one of said cranks, a shifter head slideable on the shaft of the seaming head, power transmitting connections between said shifter head and the other crank of the rock shaft of the seaming head adapted to rock said shaft to throw its seaming roll into and out of action, means for operating said shifter head, consisting of a pivoted shifting lever revolving in unison with the seaming head and engaging with one end the shifter head, and a fixed cam with which the other end of the shifter lever engages, and means for rotating the shaft of the seaming head.
12. In a can ending machine, the combination of a carrier adapted to receive and aline a can-body and its head, means for clamping and pushing the can-body into its head, a rotatable shaft upon which the carrier and clamping means are mounted whereby they revolve in unison, a flange seaming device also mounted upon said shaft and revolving in unison with the car-

rier and clamping means, said flange seaming device comprising a rotatable shaft, a head carried by the shaft, a rock shaft in the head, having a crank on each extremity, 5 a grooved seaming roll carried by one of said cranks, a shifter head slidable on the shaft of the seaming head, power transmitting connections between said shifter head and the other crank of the rock shaft of the 10 seaming head adapted to rock said shaft to throw its seaming roll into and out of action, means for operating said shifter head, consisting of a pivoted shifting lever revolving in unison with the seaming head 15 and engaging with one end the shifter head, a cam mounted loosely on the main shaft about which the several parts are revolved, and with which cam the other end of the shifter lever engages, and the means for 20 holding said cam against rotation, comprising a counter shaft connected to revolve about the main shaft, said counter shaft having a gear on each end, a fixed gear with which one of said counter shaft gears engages and a gear carried by the cam and with which the other gear of said counter-shaft engages, and means for rotating the 25 shaft of the seaming head.

13. In a can ending machine, the combination of a carrier to receive and aline a can-body and its head, means for clamping the can-body and forcing it into its head, a rotating device for seaming the flanges of the assembled body and head, a main shaft by 30 which the carrier, the clamping device and the seaming device are revolved in unison, a reciprocating presser plate carried in the axis of the seaming device and adapted to hold the head on the can while under the 35 operation of the seaming device, and means called into action by the revolution of the parts for reciprocating said presser plate.

14. A can-ending machine, comprising a horizontally revolvably journaled carrier 40 having a plurality of segmental peripheral pockets, means to deliver can bodies and heads in unison into alinement with said pockets, pairs of co-acting members alined with the pockets and one fixed relatively to 45 the other, a presser plate adapted to successively guide one side of the can end to position, to hold the end in place until the can body is pushed into it, and to retain the end in place while it is seamed upon the 50 body, and means for double-seaming the end to the body.

15. A can ending machine comprising a 55 revolvble carrier having a plurality of segmental peripheral pockets, means to deliver can-bodies and ends into alinement with said pockets, clamps consisting of stationary segments alined with the pockets, coacting segments having journals at right angles with the axes of the segments, about which 60 they are turnable to open and close, presser

plates adapted to guide and position the can ends and to retain them upon the bodies, and rollers revoluble with relation thereto to double seam and unite the heads and bodies.

16. A can ending machine including a circular revoluble carrier having peripheral segmental pockets, can-body and head chutes so alined that the lowermost bodies and heads rest upon the periphery of the carrier and drop into the pockets as the carrier 70 revolves, a guiding and presser plate slideable in alinement with the carrier, a spider having arms in alinement with the carrier pockets, a stem guided and slideable in the spider arms, clamping jaws carried by the 75 stem, one of said jaws being capable of opening and closing in an arc transverse to the carrier, and means to actuate said jaw in unison with the revolution of the carrier.

17. A can ending and seaming machine, 80 including a revoluble circular carrier having peripheral segmental pockets, each formed with three steps adapted to receive the can-body, its flange and the can-head, respectively, chutes by which the can-bodies and 85 heads are directed to rest upon the periphery of the carrier, and to fall into their respective pockets as the carrier revolves, a guided slideable stem with interior fixed and exterior swinging segmental jaws, adapted to 90 clamp the can, and by which the can is forced into the head, a presser plate, and rollers by which a double seamed joint is formed.

18. A can ending machine, including a 100 revoluble circular carrier having peripheral segmental pockets, each formed with three steps adapted to receive the can-body, its flange and the can-head, respectively, chutes by which the can-bodies and heads are directed to rest upon the periphery of the carrier, and to fall into their respective 105 pockets as the carrier revolves, a guided slideable stem with interior and exterior swinging segmental jaws, a roller carried 110 by the swinging jaw, and a fixed circumferential cam through which the roller travels to close said jaw and clamp the can.

19. A can ending machine, including a 115 revoluble circular carrier having peripheral segmental pockets, each formed with three steps adapted to receive the can-body, its flange and the can-head, respectively, chutes by which the can-bodies and heads are directed to rest upon the periphery of the carrier, and to fall into their respective 120 pockets as the carrier revolves, a guided slideable stem with interior fixed and exterior swinging segmental jaws, a roller carried by the swinging jaw, a fixed circumferential cam 125 through which the roller travels to close said jaw and clamp the can, a second roller upon the back of the jaw, and a concentric guard rail within which said roller travels.

20. A can-ending machine, including a 130

revoluble carrier with peripheral pockets, chutes to deliver can bodies and heads into the pockets into alinement, as the carrier revolves, a cam-shaft, a spider thereon, fixed 5 segmental jaws in alinement with the carrier pockets, said jaws having a stem slidably mounted in each arm of the spider, complementary hinged jaws with rollers and a cam by which said hinged jaws are opened 10 and closed, cross heads to which the stems of the fixed jaws are secured, guide rods secured to the fixed jaws and united in each of the cross-heads, and bearings in the outer ends of the arms of the spider in which said 15 rods are guided.

21. A can ending machine, including a revoluble carrier with peripheral pockets, chutes to deliver can bodies and heads into said pockets in alinement, as the carrier revolves, a cam-shaft, a spider thereon, and rotating therewith, a bearing carried by each arm of the spider, fixed segmental jaws in alinement with the carrier pockets, complementary hinged jaws with rollers and a cam 20 25 by which said hinged jaws are opened and closed, each pair of jaws having a stem slidably mounted in one of said bearings, cross-heads to which the stems of the jaws are secured, and guide rods secured to the fixed jaws and united in each of the cross-heads and guided in said bearings.

22. A can ending and seaming machine, comprising a revoluble carrier having peripheral pockets, chutes alined to deliver can bodies and heads by gravitation, in unison into the carrier pockets, as said pockets pass, clamping holding jaws, mechanism to reciprocate the jaws and enter the can-bodies into the heads, grooved seaming rolls 30 35 40 registering with the assembled can parts, and revoluble in unison with the carrier.

23. A can ending and seaming machine, comprising an axially horizontal, revoluble grooved carrier, chutes alined to deliver can-bodies and heads into the carrier pockets by 45 50 gravitation, as said pockets pass, clamping holding jaws, mechanism to reciprocate the jaws and enter the can-bodies into the heads, grooved seaming rolls registering with the assembled can parts and revoluble in

unison with the carrier, seamer heads, rock shafts journaled therein, and rockable pintles forming the connection between the seaming rolls and the means for moving said rolls.

24. A can ending and seaming machine, comprising a revoluble grooved carrier, chutes alined to deliver can-bodies and heads into the carrier pockets, by gravitation, as said pockets pass, clamping holding 55 60 65 jaws, mechanism to reciprocate the jaws and enter the can-bodies into the heads, grooved seaming rolls registering with the assembled can parts and revoluble in unison with the carrier, seamer heads, rock shafts journaled 70 75 80 therein, rockable pintles forming a connection between the seaming rolls and the means for moving said rolls, a shifting head and levers and a cam, and fixed and turnable gears to maintain the cam against relative rotation.

25. A can ending and seaming machine, comprising a revoluble carrier with peripheral pockets, chutes alined to deliver can-bodies and heads into the carrier pockets by 75 80 85 gravitation, as said pockets pass, clamping jaws and mechanism to open and close them, a reciprocating presser plate to assemble the can-body and head, seamer heads and rollers, and means whereby the mechanism is actuated continuously.

26. A continuously revoluble can-body ending machine, consisting of an axially horizontal, continuously revoluble carrier with peripheral notches adapted to receive 85 can-bodies and heads simultaneously, and in alinement, means revoluble in unison with the carrier to clamp, guide and assemble the bodies and heads, and double seaming heads and operating means therefor revoluble in 90 unison with the carrier about the main horizontal shaft.

In testimony whereof I have hereunto set my hand in the presence of two subscribing witnesses.

FRANK J. SMITH.
